UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

LATCH-NEEDLE FOR KNITTING-MACHINES.

1,175,309.

Specification of Letters Patent.

Patented Mar. 14, 1916.

Application filed August 19, 1915. Serial No. 46,248.

To all whom it may concern:

Be it known that I, ROBERT W. SCOTT, a citizen of the United States, and resident of Boston, in the county of Suffolk and State 5 of Massachusetts, have invented new and useful Improvements in Latch-Needles for Knitting-Machines, of which the following is a specification.

My invention relates to latch needles for 10 knitting-machines, and particularly to such needles so constructed as to prevent loosening of the rivet by which the latch is hung to the slotted shank of the needle.

One object of my invention is to improve 15 and simplify the construction described and claimed in my Letters Patent No. 938,795, dated November 2, 1909, for such needles.

In the accompanying drawings, Figure 1 is a vertical sectional view of one form of 20 needle; Fig. 2 is a similar view illustrating a modification; and Fig. 3 is a similar view illustrating another modification.

Referring to Fig. 1, 1 represents the shank of the needle, and 2 the ordinary latch which 25 is free to swing in a central slot 3 formed in the needle shank, the latch being pivoted to the needle by means of a rivet 4 passing through openings in the walls of the slot and through an opening at the butt end of 30 the latch, the ends of this rivet being swaged or expanded so that it serves not only as a pivot of a latch but also under normal working conditions to retain in place the walls of the slot. In the operation of the machine 35 lateral pressure is sometimes exerted upon the projecting portion of the latch, as by knots or enlargements upon the knitting yarn, which causes the walls of the slot to spread and thereby stretch or loosen the 40 rivet, so that the latter projects at one or both ends beyond said walls when the latter assume their normal position. Such a projecting portion of the rivet accumulates fibers from the yarn in a destructive manner.

As pointed out in my said patent, it is 45 necessary that the slot for the latch should extend completely through the shank of the needle at one point to provide clearance for the lint which accumulates in the slot. Ordinarily the slot is formed in the needle shank by means of a saw or like circular cutting tool forming a kerf extending completely through the shank.

In carrying out my present invention, I 55 provide for leaving a portion or integral

bridge 7 of the wall of the needle shank at the back of the latch slot 3 in a position near the latch pivot 4. As shown in Fig. 1, the hook 5 of the needle may be bent from a portion 6 of the shank swaged or otherwise reduced in the main from the back of the needle, so that a circular saw-cut α will penetrate to the back wall of the needle at a part of the slot 3 not opposite the latch pivot, but above the same, leaving a clearance opening 65 between the points y , y .

In some cases, for instance when a needle having a thin shank 11 is desired, I may obtain the benefits of the integral bridge behind the latch pivot in the manner shown 70 in Fig. 2, by reducing the body 11 of the needle from the back on the line α' , thus providing an opening between the points y' and y' beneath the latch pivot, while retaining if desired the construction above the 75 latch pivot illustrated in Fig. 1.

In some situations, for instance for needles having thick shanks 12, or in which a larger area of clearance opening is desired, a construction otherwise the same as that 80 of Fig. 1 may be provided with an opening from the back of the needle formed by a circular cut α intersecting the circular bottom α of the slot 3, but not involving the full width of the needle.

An advantage over my patented structure 85 of all of the above described structures follows from forming a clearance opening in a part reduced in cross-section for the purpose of forming a hook, thus avoiding one of the operations necessary to make the needle of my said patent, and making the improved structure adaptable to straight-front or forward-hook needles.

What I claim is:

1. A knitting machine needle having a shank and a reduced hook portion, a latch, and a slot for said latch having a bottom intersecting the back face of the needle at 100 points above the latch pivot only, whereby to leave an integral bridge structure behind the latch pivot.

2. A latch needle having a hook, a latch, a pivot, and having therein a latch slot of 105 which the bottom is a curve penetrating the back of the needle at points above the latch pivot, whereby a bridge structure for supporting the walls of the latch slot is constituted by an integral part of the material of 110

the needle shank behind and near the latch pivot.

3. A latch needle having a shank portion and a hook portion reduced in the main
- 5 from the back of the needle, a latch for the hook and a pivot for the latch, said latch swinging in a slot formed with a circular

bottom intersecting the front face of the needle and a part of the back face of the needle lying wholly within the reduced part 10 thereof.

Signed by me at Boston, Massachusetts,
this 17th day of August, 1915.

ROBERT W. SCOTT.
